(57) **CLAIM**

I claim the ornamental design for a cutting device, as shown.

DESCRIPTION

FIG. 1 is a perspective view of a cutting device showing my new design;

FIG. 2 is a bottom view of the cutting device shown in FIG. 1;

FIG. 3 is a top view of the cutting device shown in FIG. 1; FIG. 4 is a side elevation view of the cutting device shown in FIG. 1;

FIG. 5 is a front elevation view of the cutting device shown in FIG. 1; and,

FIG. 6 is a top view of the cutting device in a retracted position as shown in FIG. 1.
